UNITED STATES PATENT OFFICE.

GEORGE EDWARD BROWN, OF LOS ANGELES, CALIFORNIA.

GAME BOARD.

Application filed June 24, 1926. Serial No. 118,273.

My invention relates to a game board constructed preferably in the form of an oblong rectangle, the object of my invention is to simulate the game of hockey and in order to accomplish this object, in miniature, I have inaugurated additions and alterations, but, have retained the basic action of the game of hockey including the objective points as played and recognized on the regulation

10 hockey field.

Another object of my invention is to retain and accentuate the competitive interest and action present in the game of hockey, to further this object I provide for 15 two players to compete in controlling and manipulating the provided game piece or puck, miniature hockey sticks or clubs are provided for the manipulation or movement of this said game piece or puck and fixed 20 obstructions are positioned at various locations on this miniature board or field with the object in view of deflecting and obstructing the free movement of the game piece or puck when struck or pushed by the 25 provided sticks or clubs.

Another object of my invention is to restrict the free movement of the provided miniature sticks or clubs, to accomplish this object I provide a transparent top or cover, 30 preferably of glass, positioned slightly above the tops of the obstructions that are fixed to the board or field, thus, allowing a free lateral action of the sticks or clubs but causing the operator or player to move the 35 provided stick around the obstructions, thus, preventing the player from lifting and replacing the stick, without interference, at such positions as they may desire in their attempt to strike or push the provided game 40 piece or puck, to further control and restrict the free movement of the sticks or clubs I prefer to construct them of a flat material, preferably a flexible metal provided with a suitable handle on one end and 45 a right angle bend, tapering to a blunt point, at the opposite end, the length of this said right angle bend being approximately the same as the height of the fixed obstructions, thus, allowing the striking or pushing 50 of the game piece or puck at any position it may be located at on the board or field.

I also provide an inclosure surrounding the entire board or field, this inclosure is 55 primarily to keep the puck on and within the limits of the board or field, the ends of

this inclosure also provide a medium suitable for fastening the transparent top or cover rigidly and permanently in position, I also provide that the sides of the inclosure are constructed slightly lower than the top or transparent cover and on an approximate level with the tops of the fixed obstructions, this provision is made to allow for the free lateral movement of the provided sticks or clubs as detailed herein.

I may also mention that I provide a round hole of suitable size in each end of the inclosure, the object of these holes is to allow the insertion of the provided sticks 70 or clubs when they are not in use or required, thus, providing a self contained game board, the game piece or puck is allowed to remain in the inclosure when game board is not in use.

To further simulate the game of hockey I provide a designated position at center of board or field for the placing of the game piece or puck at the starting of the game, and I also provide at each end designated 80 positions known and referred to as goals, these goals are the objective points the players strive to cause the game piece or puck to locate in order to win the game, thus, a player's objective point is to prevent the 85 opposing player from forcing the puck towards him until it comes to rest in his goal and also to cause the puck to move towards the opponent and come to rest in his goal located at the opposite side of board or 90 field.

The action of the game in regular competition is as follows:—The game piece or puck is placed in designated position at center of board, each player then inserts a 95 stick or club in their right hand side of the game board in the slot or opening provided immediately under the transparent top or cover with the right angle bend pointing down, the point of the stick or club should be located in goal nearest to them at their 100 end of board, at the call of time both players go into action striving to force the puck over into the goal of opponent located at far side of board, bending or prying with the clubs is prohibited, if the puck should become located in a trap (places too narrow to allow puck to pass thru, and of which there are several) the problem then is to maneuver until the puck is clear of the trap 105 and proceed to continue towards the objective points until one or the other scores by 110

getting the puck inside the objective goal at opponent's end of board.

The game piece or puck used in the game may be of any suitable material or composition, I prefer to use one of metal as it eliminates rebound and altho mobile offers proper resistance.

Figure (1) of the accompanying drawing, which is a part of this petition, shows a top view of the game board, illustrating the positions and contour of the fixed obstructions which are an essential and integral part of the game board, Figure (2) shows a cross or sectional view of the gameboard and the fixed obstructions, also the transparent top or cover in its proper position and the space provided between it and the tops of the obstructions allowing for the manipulation of the provided sticks or clubs, Figure (3) shows the approximate size and contour of the provided metal puck or game piece, Figure (4) shows the character and construction of the stick or club provided for the manipulation of the metal puck, or game piece.

Relative to the drawing which is a part of this petition and attached hereto I have shown in Figure (1) a top view of the herein described hockey game board, numerals 30 —5— refer to the fixed obstructions of various shapes and their approximate location on the game board, these obstructions may be constructed of any suitable material, wood, metal or composition, in the model the construction is of wood, numeral —6— refers to the starting point where the puck is positioned at the beginning of the game, numerals —7— refer to the goals which are the objective points of play for the final positioning of the puck in order to win a game, numerals —8— refer to the sides of the inclosure and numerals —9— refer to the ends of the inclosure to which the transparent top or cover is attached. Figure (2) shows a side or sectional view of the game board, numerals —10— refer to the various obstructions positioned on the board, numeral —11— refers to the side of the inclosure cut away to clarify the details of the obstructions, numeral —12— refers to the transparent top or cover and shows it secured to ends of inclosure and positioned slightly above the tops of the obstructions and the sides of the inclosure, numeral —13— refers to the space provided for the lateral movement of the provided sticks or clubs, this space is clear and when inserted therein the provided sticks or clubs may be freely moved laterally, due to the flat construction of same, but may not be lifted to avoid contact with the obstructions and thus allow a too free and unrestricted movement of the provided clubs, numeral —14— refers to the end of the inclosure and shows also the provided construction shaped to support the transparent

top or cover, Figure (3) refers to the game piece or puck, numeral —15— shows a side view of the puck, numeral —16— shows a top view of the puck, Figure (4) refers to the provided stick or puck, numeral —17— 70 refers to the flat shank or body of the club, this shank of the club being of the same approximate length as the width of the game board, numeral —18— refers to the right angle turn or bend of the club and numeral —19— refers to the end of the right angle bend used as a point of contact when striking or pushing the puck, numeral —20— refers to the handle of the provided club, it may be noted this handle is somewhat larger than the shank or body of the club, this is to prevent long angular reaches with the club during play and cause the player to move the playing hand along with the travel of the puck, it is also required that the playing hand of the player be kept in contact with the board or table the game board may be resting upon, this requirement tends to eliminate upward prying with the provided clubs, this tendency to pry invariably becomes evident when the players get into action and their goal is in danger of opponent.

Your petitioner contends that minor changes such as shape or location of obstructions, general outline of game board or the substitution of wires in lieu of glass or transparent top or cover would in no way alter the spirit of the invention as described in detail herein.

What I claim as my invention is:—

1. In combination, a game board simulating, in miniature, the game of hockey, having fixed obstructions positioned thereon and having provided a mobile game piece known as a puck together with suitable miniature sticks or clubs designed to move or manipulate said puck, also having provided a transparent top or cover with suitable space provided between said top or cover and obstructions and sides of game board inclosure to allow for the restricted movement or manipulation of said sticks or clubs.

2. In combination, a game board simulating, in miniature, the game of hockey and having provided; fixed obstructions, a mobile game piece or puck, clubs or sticks to manipulate said game piece or puck, a transparent top or cover permitting clear vision but restricting promiscuous movements of clubs or sticks and a designated position for placing said game piece or puck at starting of game and also designated positions as objective points for location of game piece or puck at the finish of the game.

3. In combination, a game board simulating, in miniature, the game of hockey and having provided; fixed obstructions, miniature clubs or sticks of suitable design, a mobile miniature game piece or puck, a trans-

parent top or cover, a designated position for location of game piece or puck at start of game, designated positions for location of game piece or puck at finish of game and an inclosure surrounding the game board, the ends of same being used as a supporting medium for the transparent top or cover, the sides of said inclosure being constructed slightly lower than the ends and on an approximate level with the top of the

inclosed obstructions, thus, allowing for the insertion and lateral movements of the provided sticks or clubs used in manipulating and directing the movements of the said game piece or puck.

Signed at Los Angeles, Los Angeles County, State of California, this 19 day of June, 1926.

GEORGE EDWARD BROWN.
